UNITED STATES PATENT OFFICE

114,206

DESIGN FOR A BRACELET OR SIMILAR ARTICLE

Joseph B. Chorbajian, New York, N. Y.

Application March 3, 1939, Serial No. 83,304

Term of patent 3½ years

To all whom it may concern:

Be it known that I, Joseph B. Chorbajian, a citizen of the United States, residing in New York city, in the county of New York and State of New York, have invented a new, original, and ornamental Design for a Bracelet or Similar Article, of which the following is a specification, reference being had to the accompanying drawing, forming part thereof.

Fig. 1 is the plan view of a bracelet showing my design, and

Fig. 2 is a side view thereof.

I claim:

The ornamental design for a bracelet or similar article, substantially as shown.

JOSEPH B. CHORBAJIAN.
